(57) **CLAIM**

The ornamental design for a rowing machine, as shown and described.

DESCRIPTION

FIG. 1 is a front, left side perspective view of a rowing machine, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof;

FIG. 9 is a perspective view of the rowing machine in a closed position thereof;

FIG. 10 is an enlarged view of the selected portion 10 in FIG. 2;

FIG. 11 is an enlarged view of the selected portion 11 in FIG. 2;

FIG. 12 is an enlarged view of the selected portion 12 in FIG. 7;

FIG. 13 is an enlarged view of the selected portion 13 in FIG. 9;

FIG. 14 is an enlarged view of the selected portion 14 in FIG. 9; and,

FIG. 15 is an enlarged view of the selected portion 15 in FIG. 9.

The broken lines shown in the drawings depict portions of the rowing machine that form no part of the claimed design.

1 Claim, 15 Drawing Sheets
